Letter of Millions of Hamilton County, State of Ohio

Letters Patent

The schedule referred to in these Letters Patent and making part of the same, containing a description in the words of the said John S. Millions himself of his improvement in Roads.

To all to whom these presents shall come:

Be it known that I, John S. Millions, of Hamilton County and State of Ohio have invented a new and useful improvement in the construction of Roads, whereby some of the advantages derived from rail roads are attended to the common carriages of burthen or pleasure, that travel any road as improved and that the following is a full and exact description of my said improvement, — I lay two ^{timed} continuous^{timed} of timber or other suitable material, lengthwise on said road, such a distance apart as to form tracks for the wheels of such vehicles, as are in general use upon the road so improved. I furrow, gutter, or groove one of these tracks in order to receive and guide the wheel or wheels on one side of the carriage travelling thereon. These grooves or gutters may be made in the timber or other material before it is laid upon the road or afterwards in either by hand or by machinery propelled by any suitable motion power or they may be formed by attaching blocks so as to a plain surface.

The other track ought to be laid on a level with the bottom of the furrow or gutter above mentioned, — The plain road ought to be of such a width as to allow for the carriage of four or more horses, given to the wheels of different kinds of carriages in some places so that while the wheels of one car of the vehicle shall remain within the groove of one track, the other wheel shall remain on the face of the other track commanding the different spans to which

they may be immovable - These tracks may be beaten or laid down upon stone, gravel, clay, or any material of which the surface of the road is formed and the pieces of which they are constructed may be connected by dovetails, or cleamps, or laid upon transverse blocks or caps pieces, which may or may not, extend from one to the other, —

Scrapers may be attached to some of the carriages passing on said tracks for the purpose of clearing them of stones, earth, or other matter, which might tend to obstruct the wheels or injure the tracks —

When there is much travelling upon a road so improved, lay two sets or four continuous lines of tracks one set for the going and one for the returning carriage, this will be found most convenient, as it is to turn out of the tracks when carriages meet will not be attended with difficulty, as one side only of the turning out carriage would have to be raised over a small obstacle —

I am aware that some of the advantages of such a track road may be gained by laying timber this as above and by furrowing, guttering or rebating both tracks to guide the wheels but I prefer to gutter or groove one only —

What I claim as my invention or improvement is the laying of tracks of wood or other suitable material, one of which shall be furrowed grooved or guttered in the manner and for the purpose herein before set forth —
